No. 703,894.

Patented July 1, 1902.

M. CHOQUETTE.
SHINGLING BRACKET.

(Application filed Sept. 25, 1901.)

(No Model.)

UNITED STATES PATENT OFFICE.

MICHEL CHOQUETTE, OF KANKAKEE, ILLINOIS.

SHINGLING-BRACKET.

SPECIFICATION forming part of Letters Patent No. 703,894, dated July 1, 1902.

Application filed September 25, 1901. Serial No. 76,515. (No model.)

To all whom it may concern:

Be it known that I, MICHEL CHOQUETTE, a citizen of the United States, residing at Kankakee, in the county of Kankakee and State 5 of Illinois, have invented a new and useful Shingling-Bracket, of which the following is a specification.

This invention relates to shingling-brackets of that class adapted for engagement with 10 fixed or applied shingles or roofing elements to support one end of a scaffold or board whereby the operator is enabled to superpose other shingles in his progress toward the comb or apex of the roof; and the object had in 15 view is to provide a device of this kind which may be applied with facility to the exposed lower edges of secured shingles and may be held effectively in place to support the weight of the scaffold and its occupant.

With these and other objects in view, as 20 will appear as the nature of the invention is better understood, the same consists in the novel construction and combination of parts of a shingling-bracket, as will be hereinafter 25 fully described and claimed.

In the accompanying drawings, forming a 30 part of this specification, and in which like numerals of reference indicate corresponding parts, there is illustrated a form of embodiment of the invention capable of carrying the 35 same into practical operation, it being understood that the elements herein exhibited may be varied or changed as to shape, proportion, and exact manner of assemblage without de- 40 parting from the scope of the invention, and in these drawings—

Figure 1 is a view in side elevation, exhibiting the bracket applied to a roof. Fig. 2 is a detached detail perspective view of the bracket.

Referring to the drawings, 1 designates, 45 generally, the bracket, comprising a stationary base member 2, a pivoted clamping member 3, an adjustable scaffold-rest 4, and a rest-adjusting link 5.

The base member 2 comprises a plate of 50 metal having a longitudinally-disposed up-standing reinforcing-rib 6 and is provided at one end with a flat jaw or plate 7, provided on its upper face with a plurality of studs or prongs 8 and at its opposite end with two prongs or feet 9, which extend below the under surface of the plate and are designed

to bite into the roof member upon which this end of the bracket rests. The base member is provided adjacent to the jaw 7 with an up-standing bifurcated boss 10, between which is pivoted the clamping member 3, a bolt or screw 11 serving to hold the clamping member associated with the boss. The rear end of the clamping member carries a clamping- 55 screw 12, which is adapted to engage with a bearing-surface 13 on the rib 6, thereby to move the forward end of the clamping member to or from the jaw 7, and carried by said outer end of the clamping member and pivotally connected therewith is a jaw 14, provided on its undersurface with studs or prongs 15, adapted to coact with those on the jaw 7 to effect clamping and securing of the bracket to a shingle or board on the roof. In order 60 to effect the most efficient securement of the bracket to the roof member, the prongs of the two jaws are by preference arranged in staggered or break-joint order, by which arrangement it will be seen that a larger area of 65 the roof member will be engaged by the prongs than if the same were arranged in aligned order, so that when the jaws are once clamped to the roof member the bracket will be held securely in place. Any suitable means may 70 be employed for securing the jaw 14 to the clamping member 3, the means in this instance employed being to provide the jaw 14 with a bifurcated boss 16, through which passes a screw or bolt 17 to connect it pivot- 75 ally with the clamping member 3.

The adjustable scaffold-rest 4 comprises a plate provided on its upper edge with a plurality of prongs or steps 18, which operate to hold the scaffolding against shifting rearward 80 in the use of the device, whereby the carpenter will always be within easy reach of the work to be done. Near the forward end of the rest 4 and on the under side thereof are provided two ears 19, adapted to straddle the 85 outer end of the clamping member 3, and through these ears and the clamping member is passed a bolt or screw 20 to effect pivotal connection between the parts. The rear end portion of the rest 4 carries a transversely- 90 disposed pin 21, the ends of which are designed to engage recesses or seats 22, formed in the rear upper portion of the rest-adjusting link 5, the recesses by preference being 95 100

curved inward and downward, thereby to prevent accidental separation of the pin therefrom in the event of the locking means, presently to be described, not being in position 5 to lock the rest and link against separation. The link comprises a strip of metal bent upon itself to present a yoke, and the lower extremities thereof are held assembled with the rib by a bolt 23, the rear portion of 10 the clamping member being passed between the yoke members and being guided thereby and held from lateral play. The link is curved rearward from the rest 4 to correspond with the arc described by the rear end of the rest 15 when the same is being adjusted to cause it to occupy a horizontal plane irrespective of the pitch of the roof being shingled. To hold the rest in adjusted relation with the link, a pivoted locking-latch 24 is associated with the 20 rest, the latch being provided with a laterally-extending projection 25 to engage a notch 26, formed in the rest contiguous to the front wall of the link. When the projection is in engagement with the notch 26, as shown in Fig. 1, dis- 25 engagement of the pin members from the recesses of the link will be positively prevented, and to effect adjustment of the rest it will only be necessary to close the latch to the position indicated by dotted lines in the said figure, 30 rock the link toward the forward end of the bracket to throw the pin out of engagement with the recess thereof, and then move the rest up or down, as may be required, and then bring the locking-latch again into en- 35 gagement with the notch.

When the bracket is to be placed in position upon a roof, the lower jaw 7 is inserted under a shingle that has been nailed or under a board, as shown in Fig. 1, and the 40 clamping-screw 12 is turned down, thereby forcing the jaw 14 down upon the roof member and causing the respective teeth or prongs of the two jaws to bite into the roof member. The rest 4 is then adjusted in the manner al- 45 ready described to bring it to a horizontal position, after which the scaffold or board is placed on the rest. The weight of the scaf- fold and its occupant will cause the rear prongs 9 to bite into the shingles, thereby 50 presenting a holding means supplemental to the prongs or teeth of the jaws to hold the bracket from slipping or becoming detached from the roof member.

It will of course be understood that two of 55 these brackets are to be employed, and as

this will be obvious illustration thereof is deemed unnecessary.

By having the jaw 14 pivotally associated with the clamping member the same is rendered automatically adjustable to the surface 60 against which it contacts, so that positive clamping of both sides of the piece of wood or the like will positively be effected whether such wood be of the same thickness throughout its length or tapered, as in the case of a 65 shingle.

It will be seen from the foregoing description that while the device of this invention is exceedingly simple of construction the arrangement and disposition of its parts are 70 such as to present a device that will be thoroughly efficient in operation for the purposes designed.

Having thus fully described the invention, what I claim as new, and desire to secure by 75 Letters Patent, is—

1. A shingling-bracket comprising a base member provided at one end with a toothed extension for insertion beneath the free edges of a shingle and at its opposite end with 80 prongs, a clamping member pivoted to the base member and carrying a movable toothed jaw, a scaffold-rest carried by one end of the clamping member, a rest-adjusting link carried by the base member and provided with 85 seats or recesses to be engaged by offsets carried by the scaffold-rest, and means for adjusting the clamping member with relation to the base member.

2. A shingling-bracket comprising a base 90 member provided at one end with a toothed extension for insertion beneath the free edges of a shingle and at its opposite end with prongs, a clamping member pivoted to the base member and carrying a movable toothed 95 jaw, a scaffold-rest carried by one end of the clamping member, a rest-adjusting link carried by the base member and provided with seats or recesses to be engaged by offsets carried by the scaffold-rest, means for adjusting 100 the clamping member with relation to the base member, and locking means carried by the scaffold-rest.

In testimony that I claim the foregoing as my own I have hereto affixed my signature in 105 the presence of two witnesses.

MICHEL CHOQUETTE.
